Design No. 418.
Chair of Motions
Chair of Design Committee. Patented June 14, 1895.

Des. 418

Charles J. Woolson, of Cleveland, O.
Letters Patent No. 418. Dated, Oct. 14. 1851.

~~~~~  
The schedule referred to in these Letters Patent & making part  
of the same. —

~~~~~  
To all whom it may concern! Be it known that I,

Charles J. Woolson, of Cleveland, State of Ohio, have invented a new & useful design for stoves, and I hereby declare that the following is a full & exact description thereof, reference being had to the accompanying drawings, in which my design is clearly represented.

The shape & configuration of the front plate of the stove, is designated by the general outline of the drawing, and the ornamental work at the sides, and above & below the doors, (or the opening for the fire place) is seen at A,A,A,A,A.—

The serpentine ornamental work upon the front of the Register, is seen at B,B.—

The ornamental design from which the arm springs which supports the door, is seen at E.— The arm & hand are seen at E.E.— The arm & hand usually form part of a hinge, and separate in turning, or folding at G,G,G,G. The ornamental work upon the doors is shown at H,H. The front edge of the doors, when they are opened, forms part of the ornamental twisted work upon the outer edge of the front of the stove, as seen at K. The door arm & hand are seen separately & respectively at I,M,N.— The Hearth plate or bottom of the stove, is seen at O. The ornamental work is seen at P,P,P.— The apron or cover to the Ash pit is seen at R, with its ornamental & fluted work.

A perspective view of the stove is seen at 'I', with one door open & the other closed.—

What I claim as my invention and wish to secure by Letters Patent, is the ornamental design and general configuration of the parts of my stove as herein designated & represented.

Witnesses.

H. G. Hitchcock,
L. S. Cleveland,

Charles J. Woolson 400
